GRINDING WHEEL TRUING ATTACHMENT

Raymond A. Cole, Worcester, Mass., assignor to
 Norton Company, Worcester, Mass., a corpora-
 tion of Massachusetts

Application July 30, 1935, Serial No. 33,868

10 Claims. (Cl. 125—11)

This invention relates to grinding machines, and more particularly to a grinding wheel truing apparatus for truing the operative face of a grinding wheel.

It is one of the objects of this invention to provide a simplified, thoroughly practicable truing apparatus for truing the periphery of a grinding wheel to a predetermined form or contour.

Another object of this invention is to provide 10 a self-contained power operated truing apparatus for producing a predetermined form on the operative face of the grinding wheel.

It is another object to provide a truing apparatus which permits the truing of a grinding 15 wheel to the desired form without the necessity of removing the work from its operative position within the grinding machine. Other objects will be apparent from the foregoing specifications.

20 The invention accordingly consists in the features of construction, combinations of elements, and arrangements of parts as will be exemplified in the structure to be hereinafter described, and the scope of the application of which will be indicated in the following claims.

25 In the accompanying drawing, in which is shown one of the various possible embodiments of the mechanical features of this invention,

Fig. 1 is an end elevation of the improved truing apparatus;

Fig. 2 is a front elevation of the truing apparatus, partly in section, on an enlarged scale, taken approximately on the line 2—2 of Fig. 1;

Fig. 3 is a fragmentary rear elevation of the 30 adjustable support for the truing apparatus;

Fig. 4 is a cross sectional view of the truing tool, on an enlarged scale, taken approximately on the line 4—4 of Figs. 1 and 2;

Fig. 5 is a cross sectional view, on an enlarged 40 scale, taken approximately on the line 5—5 of Fig. 1, showing the mounting and adjustment of the forming bar;

Fig. 6 is a fragmentary sectional view, on an enlarged scale, taken approximately on the line 45 6—6 of Fig. 5, showing the means for adjusting the forming bar; and

Fig. 7 is a cross sectional view, on an enlarged scale, taken approximately on the line 5—5 of Fig. 1, showing the arrangement of the forming 50 bar support.

The embodiment of the invention selected for illustration comprises a frame 10 which supports a transversely movable slide 11 on a dovetailed slideway 12. The slide 11 is provided with a 55 downwardly extending portion 15 which serves

as a guide and to take up the end thrust of a pivotally mounted truing tool holder 16 as it swings on its pivots during a truing operation. The slide 11 carries a pair of outwardly extending bosses 17 and 18 (Fig. 2) each of which is provided with a pivot screw 19 and 20 respectively. The screws 19 and 20 are provided with conical pivot ends which engage conical apertures in the truing tool holder 16.

The lower end of the truing tool holder 16 is 10 provided with a forwardly extending boss 25 which has a central aperture 26 supporting a diamond or truing tool 27. The diamond 27 is preferably mounted in a cylindrical holder 28 which fits in aperture 26 and is held therein by means 15 of a screw 29. The truing tool holder 16 also carries at its lower end on its rear face a follower 30 which is arranged to engage a forming bar 31. As illustrated, in the drawings the forming bar 31 is supported on the frame 10 and is 20 preferably formed as a flexible steel bar which is arranged so that its curvature may be adjusted to a deflection curve so as to cause a transverse movement of the diamond or truing tool 27 toward and from the wheel axis as it is traversed 25 transversely of the frame to generate a deflection curve upon the periphery of the grinding wheel.

The diamond truing tool holder 16 is provided with rearwardly extending bosses 40 and 41 which 30 engage surfaces 42 and 43 of the downwardly extending portion 15 of the slide 11 and serve to guide and steady the diamond tool holder 16 as slide 11 is reciprocated.

The truing tool slide 11 may be reciprocated 35 by any suitable means such as, for example, a power operated mechanism comprising a nut 50 in slide 11 which is engaged by a screw 51 rotatably supported in a bearing 52 in the frame 10. The screw 51 is held against endwise movement by means of the bearing 52 on frame 10 and may be rotated by any suitable means such as, for example, a power operated mechanism comprising an electric motor 55 which is provided with a pulley 56 mounted on a motor shaft 57, 45 and which drives a pulley 58 mounted on the end of feed screw 51 by means of a driving belt 59. The motor 55 is preferably of the reversible type and is arranged so that it may be connected by wiring in a conduit 60 to a reversing switch 61 which is controlled by a manually operable lever 62. The power to operate the motor is supplied from any suitable source through a wire conduit 63. By operating the switch handle 62, the motor may be caused to rotate in either di- 50 55

rection to cause the screw 51 to rotate and, through nut 50, to move the slide 11 carrying the truing tool holder 16 and truing tool 27 transversely relative to the operative face of a grinding wheel 70.

A yieldable pressure device is provided to hold the truing tool holder 16 with the follower 30 always in operative engagement with the forming bar 31. The pressure device may comprise a 10 stud 72 which is threaded into a rearwardly extending boss 73 on diamond or truing tool holder 16. The stud 72 passes through a clearance hole 74 in the portion 15. A spring 75 surrounds the stud 72 and rests in a counterbored aperture 76 15 in the slide 15 and is interposed between the bottom of the counterbore and a collar 77 which is held in place on stud 72 by means of a nut 78. By adjusting the nut 78 along the stud 72, the tension of the spring 75 may be adjusted to hold 20 the follower 30 in contact with the forming bar 31 with the desired pressure.

The forming bar 31 is supported at its opposite end by means of a pair of substantially U-shaped blocks 80 and 81 which are held in place on the 25 slide 15 by screws 82 and 83 respectively. The center of the forming bar 31 is engaged by a substantially C-shaped head 85 of a bolt 86. The ends 87 and 88 of the C-shaped head wrap around and engage the front surface of the forming bar 30 31. The bolt 86 passes through a hole 89 in the depending portion of the frame 10 and is provided with a threaded portion 90 at its outer end which is engaged by a nut 91. By adjusting the nut 91, the C-shaped head 85 may be adjusted to 35 flex or release the forming bar 31 so that it assumes the desired concave deflection curve to generate the desired convex curved surface on the periphery of the wheel as the slide 11 is traversed to carry the diamond or truing tool 27 across the 40 operative face of the wheel 70.

In the grinding of large cylindrical objects, such as massive rolls, which frequently weigh several tons, used in steel rolling mills, it is desirable to provide a truing apparatus which may 45 be positioned on the machine to true the operative face of the grinding wheel to the desired shape or form without the necessity of removing the heavy work piece from the machine. In the preferred construction, the truing apparatus is 50 preferably supported by a substantially U-shaped frame 95 which is arranged to straddle a work piece 96. The U-shaped frame 95 is provided with enlarged supporting pads 97 and 98, 99 and 100 which serve as a support for the supporting pads 55 101 and 102 respectively on the frame 10. The frame 10 is bolted in position on pads 101 and 102 by means of screws 103, 104, 105 and 106 to hold the truing apparatus rigidly in position on the U-shaped frame 95. The front end of the 60 U-shaped frame 95 is provided with a work engaging surface 110 which is arranged to rest upon the periphery of the roll 96 at a point adjacent to the line of contact between the grinding wheel and work piece.

65 The other end of the U-shaped frame 95 is pivotally connected by a stud 111 to a slide 112 which is arranged to move transversely of the machine on slideways 113 on a slide 114. The slide 112 is provided with a nut 115 meshing with a screw 70 116 which may be turned by means of a knob 117 to adjust the position of the slide 112 transversely of the machine. The slide 114 is adjustably positioned on slideway 118 (Figs. 1 and 2) which is formed on a supporting frame 119 and 75 may be clamped in adjusted position thereon by

means of the clamping bolts 120 and 121. The frame 119 is provided with a dovetailed surface 125 which is arranged to mate with a corresponding surface on a swivel table 126 of the grinding machine. Frame 119 may be clamped in adjusted position on the swivel table 126 by means of a clamping gib 127. The swivel table 126 is pivotally mounted in the usual manner by means of a pivot pin 128 on a longitudinally movable work supporting table 129 which is adapted to be reciprocated longitudinally of the machine on a base 130.

The slide 114 is provided to permit setting up the truing apparatus for straddling a predetermined size of roll being ground and provides a quick shift in setting up the machine for truing a wheel when a different size roll is to be ground. The knob 117 and screw 116 are provided to give a fine transverse adjustment of the supporting frame 95 after the slide 114 has been locked in 20 an operating position.

In order that the U-shaped frame 95 may be adjusted into proper relation and supported by the roll 96 being ground, it is desirable to provide an adjustable shoe 135 which is arranged to engage the upper portion of the roll 96 to support the U-shaped frame 95 and the truing apparatus frame 10. The shoe 135 is adjustably mounted on the frame 95 and is connected by a pivot pin 136 with an adjusting screw 137 which may be rotated by means of a knob 138 to adjust the truing tool 27 in a substantially vertical direction into the desired operating position.

In order that the truing apparatus may be readily inserted on the machine or removed therefrom after truing, it is desirable to provide a suitable readily detachable connection which is illustrated and comprises a pivot pin 111 having an end portion which is provided with the slabbed-off surfaces 140 and 141. The frame 40 95 is provided with a cylindrical hole 142 of a diameter equal to the diameter of the stud 111 and at its lower portion is provided with an opening 143 which is of a width slightly greater than the distance between the slabbed-on surfaces 140 and 141. When it is desired to remove the truing apparatus from the machine, the frame 95 may be rocked in a clockwise direction (Fig. 1) to swing the opening 143 into alignment with the slabbed-off surfaces 140 and 45 141 and the frame 95 may then be moved toward the right as viewed in Fig. 1 and the entire assembly removed from the machine so that the grinding operation on the roll 96 may be resumed. After the grinding has continued 50 and it is desired to again true the wheel, the frame 95 may be readily inserted in its former position with the pivots 111 supporting the end of the frame 95 and the pad 110 and adjustable pad 135 resting on the surface of the roll 96. If the roll has been reduced in diameter, the 55 operator may compensate for this reduction so that the truing tool is in the same relative position to the wheel and wheel axis by adjusting the knobs 138 and 117.

The forming bar 31 and its supporting and adjusting arrangement, as shown in Figs. 5 and 6, is adapted for use in producing a convex surface, such as a convex deflection curve on the peripheral operative surface of the grinding 70 wheel.

In the grinding of certain types of rolls, it is desirable to provide a concave curve, such as a concave deflection curve, on the peripheral operative face of the grinding wheel. In such a 75

case, a modified mounting for the forming bar 31, such as shown in Fig. 7, may be provided. The ends of the bar 31 (Fig. 7) may be supported by bolts 150 and 151 which are provided with substantially C-shaped heads 152 and 153 respectively. An adjusting screw 155 engages a threaded hole 156 in the depending portion of frame 10. The end of screw 155 engages the center of forming bar 31 and serves to flex the bar to a curve of the desired extent so that when slide 11 is traversed, the truing tool 27 will be moved transversely to true a concave curve, such as a concave deflection curve, on the peripheral operative surface of the grinding wheel.

Having thus described my invention, what I claim as new and desire to secure by Letters Patent is:

1. A grinding wheel truing apparatus for grinding machines comprising a frame, a reciprocable slide thereon, means to reciprocate said slide, a truing tool carried by said slide, means including a forming bar to move the tool transversely when the slide is reciprocated so as to produce a predetermined form or contour on the operative face of the grinding wheel, and means to adjust the position of the frame to vertically adjust the path of the truing tool relative to the grinding wheel so as to modify the contour produced by said tool on the face of the grinding wheel.

2. A grinding wheel truing apparatus for grinding machines comprising a frame, a reciprocable slide thereon, power operated means to reciprocate said slide, truing tool carried by said slide, means including a flexible forming bar and follower to move the tool transversely when the slide is reciprocated, means to support the opposite ends of said bar, and adjusting means engaging the center of said bar to flex said bar to a deflection curve so as to produce a deflection curve on the grinding wheel face.

3. A grinding wheel truing apparatus for grinding machines comprising a frame, a reciprocable slide thereon, means to reciprocate said slide, a truing tool carried by said slide, means including a flexible forming bar to move the tool transversely when the slide is reciprocated so as to produce a predetermined contour on the operative face of the grinding wheel, means to flex said bar to vary the contour of said face, means to removably attach said frame to the grinding machine, and means to adjust the position of said frame to vary the path of the truing tool relative to the face of the grinding wheel.

4. A grinding wheel truing apparatus for grinding machines comprising a frame, a reciprocable slide thereon, means to reciprocate said slide, a truing tool carried by said slide, means including a flexible forming bar to move said tool transversely when the slide is reciprocated so as to produce a predetermined form on the operative face of the wheel, means to adjust the position of the frame to vary the path of the truing tool relative to the wheel, and means to flex said forming bar to vary the shape produced on said wheel.

5. A truing apparatus for grinding machines comprising a frame, a reciprocable slide on said frame, means to reciprocate the slide longitudinally relative to the frame, a substantially vertical truing tool holder, pivotal connections between the upper end of said holder and the slide, a truing tool mounted on the lower end of said

holder, a follower on the lower end of said holder opposed to the truing tool, a flexible forming bar having its opposite ends supported on said frame and arranged to be engaged by said follower, means to maintain the follower in engagement with said bar, and adjustable means engageable with the bar midway between its supports to flex said bar so as to produce a deflection curve on the face of said grinding wheel.

6. A roll grinding machine of the type having a rotatable grinding wheel and a rotatable work support which are movable longitudinally and transversely relative to each other, and a truing apparatus comprising a substantially U-shaped frame arranged to straddle a work piece, a supporting shoe on said frame adjacent to said wheel, a reciprocable slide supported adjacent one end of said frame, a truing tool carried by said slide, means to reciprocate said slide to traverse the truing tool across the operative face of the grinding wheel, detachable connections between the other end of said frame and the machine, and means to adjust the position of said connections to maintain said shoe in an operative position.

7. A roll grinding machine of the type having a rotatable grinding wheel and a rotatable work support which are movable longitudinally and transversely relative to each other, and a truing apparatus comprising a substantially U-shaped frame arranged to straddle a work piece, a reciprocable slide supported adjacent one end of said frame, a truing tool carried by said slide, means to reciprocate said slide, means including a flexible forming bar which is supported at its ends to move said tool transversely when the slide is reciprocated to produce a predetermined contour on the wheel face, adjustable means engaging the center of said bar to flex it so as to produce a deflection curved face on said grinding wheel and detachable connections between the other end of said frame and the machine.

8. A roll grinding machine of the type having a transversely movable rotatable grinding wheel, a longitudinally movable work supporting table, a rotatable work support thereon, and a truing attachment comprising a substantially U-shaped frame, a reciprocable slide on one end of said frame, a truing tool carried by said slide, means to reciprocate said slide to traverse the truing tool across the face of the grinding wheel, detachable connections between the other end of said frame and the work table, and a work engaging shoe adjustably positioned on said frame and arranged to engage the work on its upper surface so as to adjust the position of said frame so as to vary the path of the truing tool relative to the grinding wheel.

9. A roll grinding machine of the type having a transversely movable rotatable grinding wheel, a longitudinally movable work supporting table, a rotatable work support thereon, and a truing attachment comprising a substantially U-shaped frame, a reciprocable slide on one end of said frame, a truing tool carried by said slide, means to reciprocate said slide to traverse the truing tool across the face of the grinding wheel, detachable connections between the other end of said frame and the work table, a work engaging shoe on the tool end of said frame arranged to engage the work at a point adjacent the line of contact between the work and wheel, and a second work engaging shoe adjustably positioned on said frame and arranged to engage the work on its upper surface so as to adjust the position of

said frame so as to vary the path of the truing tool relative to the grinding wheel.

10. A roll grinding machine of the type having a rotatable grinding wheel, a longitudinally movable work supporting table, a rotatable work support thereon, and a truing attachment therefor, comprising a substantially U-shaped frame arranged to straddle the work piece, a reciprocable slide mounted adjacent one end of said frame, a truing tool carried by said slide, means to reciprocate said slide relative to the frame to traverse the truing tool across the face of the grinding wheel, a work engaging shoe on said frame adja-

cent to said slide which is arranged to engage the work at a point adjacent the line of contact between the wheel and work, a detachable connection between the other end of said frame and the table, means to adjust the position of said connection transversely relative to the table so as to maintain the shoe in contact with the work, and an adjustable shoe mounted on said frame and arranged to engage the upper surface of said work to permit adjustment of said frame to vary 10 the path of the truing tool relative to the face of the grinding wheel. 5

RAYMOND A. COLE.
